UNITED STATES PATENT OFFICE.

JOHN SHIELDS, OF DALLAS, TEXAS.

ADJUSTABLE BRACE FOR DOORS OR GATES AND COVER FOR SAME.

SPECIFICATION forming part of Letters Patent No. 740,383, dated September 29, 1903.

Application filed February 20, 1903. Serial No. 144,310. (No model.)

To all whom it may concern:

Be it known that I, JOHN SHIELDS, a citizen of the United States, residing at Dallas, in the county of Dallas and State of Texas, have invented certain new and useful Improvements in Adjustable Braces for Doors or Gates and Covers for Same; and I do hereby declare the following to be a full, clear, and exact description of the invention, such as will enable others skilled in the art to which it appertains to make and use the same.

My invention relates to improvements in adjustable braces for use in preventing the sagging of swinging doors, gates, or the like and also an improved cover for the same, which invention will be understood by reference to the accompanying drawings, in which the same parts are indicated by the same letters throughout the several views.

Figure 1 is a front view of a door fitted with my improved device. Fig. 2 is a detail perspective view showing the adjustable brace. Fig. 3 is a perspective view of a cover which may be used with the device.

A represents the door, having the edge strip A' next the hinges C, by which it is connected to the frame B. Owing to the weight of the door, its edges a and a' have a tendency to swing over to the position indicated

in dotted lines in Fig. 1, thus striking either the frame or the door-sill and causing the door to jam or even prevent closing of the same. My invention is intended to remedy this trouble, and for this purpose I use an

adjustable brace D, comprising the vertical member D' and the foldable members D² and D³. In the drawings I have illustrated D' and D² as hinged together and the member D³ hinged at its lower end to the member D';

but it is obvious that any other suitable arrangement may be employed whereby the angular position of the members D² and D³ may be changed relatively to the member D'. The member D' is provided with bolt-holes d' and

is secured to the strip A'. The member D² is provided with screw-holes d² and is secured to the cross-piece A² of the door. This member D² is indented at d at its lower edge to engage the upper end d³ of the swinging member D³.

E is a spring under tension which tends to swing the member D³ upward about its hinge.

When the adjustable brace is applied, it will only be necessary to lift up forcibly on the knob of the door or to force a wedge between the door and the door-sill beneath the knob until the door is brought to the proper position, when the head d³ of the member D³ will engage one of the teeth d and will hold the door in the proper position.

To protect the brace and add an ornamental feature thereto, the same may be inclosed in an ornamental bracket or cover, such as that shown in Fig. 3. This cover is composed of two parts F and H, which are free to slide upon each other along the edge H'. The member F is provided with a face-plate F', having lugs with screw-holes f' therein, and these lugs are placed between the member D' of the adjustable brace and the strip A' of the door, and the same screws or nails pass through the holes d' and f', thus securing both the brace and its cover to the door. In the same way the upper member H is provided with a face-plate H², having lugs H' and screw-holes h² arranged to be secured between the member D² of the adjustable brace and the cross-piece A² of the door.

Since this bracket or cover will project beyond the face of the door, I preferably make the same ornamental in form, and the upper member H may be further utilized as a mailbox. Thus it may have a bottom plate H', and the front plate H³ may be hinged thereto, as at h, and provided with a lock h³.

The face-plate H² may be slotted, as at h⁴, like an ordinary mail-box. Thus it will be seen that I provide an automatically-adjustable brace which corrects the sagging down of doors and also an appropriate cover for the same which may be used as an ornamental mail-box or as a card-receiver. I do not confine myself to any particular form or shape of bracket or cover or of any particular material out of which the same may be made.

It will be obvious that should the door sag on the hinge side or tip up on the knob side the brace may be placed above the cross-piece of the door, and the outer edge of the door may be wedged or weighed down until the brace engages and holds it in the desired position.

It will be obvious that the same device whether with or without the cover may be

applied to gates, wire screens, or the like swinging barriers.

Having thus fully described my invention, what I claim, and desire to secure by Letters Patent of the United States, is—

1. The combination with a swinging door or gate, having a vertical upright piece to which the hinges are secured, and having a horizontal cross-piece, of an adjustable brace, having a horizontal member secured to the cross-piece of the door and provided with teeth on the under side thereof, a vertical member foldably connected to the horizontal member and secured to the vertical piece of the door, and a third member foldably connected to the vertical member and having its free end adapted to engage said teeth, with a spring under tension connecting said second and said third members, substantially as described.
2. In an adjustable brace for doors and the like, the combination with two members hinged together and adapted to be fastened to the door at an angle with each other, the first of which members is provided with teeth, of a third member hinged to the second and having its free end adapted to engage said teeth, a spring under tension connecting the second and third members, and a cover secured to the door over said adjustable brace protecting the same, substantially as described.
3. The combination with a swinging door or gate, having a vertical upright piece to which the hinges are secured, and having a horizontal cross-piece, of an adjustable brace, having a horizontal member secured to the cross-piece of the door and provided with teeth on the under side thereof, a vertical member hinged to the horizontal member and secured to the vertical piece of the door, and a third member hinged to the vertical member and having its free end adapted to engage said teeth, with a spring under tension connecting

said second and said third members, and a cover secured to the door over said adjustable brace protecting the same, substantially as described.

4. In an adjustable brace for doors and the like, the combination with two members hinged together and adapted to be fastened to the door at an angle with each other, the first of which members is provided with teeth, of a third member hinged to the second and having its free end adapted to engage said teeth, a spring under tension connecting the second and third members, and a cover composed of two parts each in the form of a sector secured to the door over said brace, the upper sector of said cover being provided with a slot and a door, and serving both as a cover and a mail-box, substantially as described.

5. The combination with a swinging door or gate, having a vertical upright piece to which the hinges are secured, and having a horizontal cross-piece, of an adjustable brace, having a horizontal member secured to the cross-piece of the door and provided with teeth on the under side thereof, a vertical member hinged to the horizontal member and secured to the vertical piece of the door, and a third member hinged to the vertical member and having its free end adapted to engage said teeth, with a spring under tension connecting said second and said third members, and a cover composed of two parts, each in the form of a sector secured to the door, the upper sector of said cover being provided with a slot and a door and serving both as a cover and a mail-box, substantially as described.

In testimony whereof I affix my signature in presence of two witnesses.

JOHN SHIELDS.
